CLAIM

The ornamental design for a sausage end declipper, as shown and described.

DESCRIPTION

FIG. 1 is a top view of an ornamental sausage end declipper showing my new design;

FIG. 2 is a bottom view thereof;

FIG. 3 is a first side view thereof;

FIG. 4 is a second side view thereof;

FIG. 5 is a front view thereof;

FIG. 6 is a rear view thereof;

FIG. 7 is a first side perspective view thereof; and,

FIG. 8 is a second side perspective view thereof.

The broken lines represent portions of the article and form no part of the claimed design.
